(57) **CLAIM**

The ornamental design for a fridge, as shown and described.

DESCRIPTION

FIG. 1 is a front view of one embodiment of a fridge, showing my new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a perspective view thereof.

FIG. 8 is an enlarged view of a portion of the fridge taken from FIG. 7.

FIG. 9 is a front view of another embodiment of a fridge, showing my new design.

FIG. 10 is a rear view thereof.

FIG. 11 is a left side view thereof.

FIG. 12 is a right side view thereof.

FIG. 13 is a top view thereof.

FIG. 14 is a bottom view thereof.

FIG. 15 is a perspective view thereof.

FIG. 16 is an enlarged view of a portion of the fridge taken from FIG. 15.

FIG. 17 is a front view of another embodiment of a fridge, showing my new design.

FIG. 18 is a rear view thereof.

FIG. 19 is a left side view thereof.

FIG. 20 is a right side view thereof.

FIG. 21 is a top view thereof.

FIG. 22 is a bottom view thereof.

FIG. 23 is a perspective view thereof; and,

FIG. 24 is an enlarged view of a portion of the fridge taken from FIG. 23.

The broken lines depict portions of the fridge that form no part of the claim.

1 Claim, 18 Drawing Sheets
